DESIGN FOR A CONTROL INSTRUMENT CASING

Henry Dreyfuss, New York, N. Y., assignor to
Minneapolis-Honeywell Regulator Company,
Minneapolis, Minn., a corporation of Delaware

Application January 9, 1941, Serial No. 97,912

Term of patent 14 years

To all whom it may concern:

Be it known that I, Henry Dreyfuss, a citizen of the United States, residing at New York city, in the county of New York, and State of New York, have invented a new, original, and ornamental Design for Control Instrument Casing, of which the following is a specification, reference being had to the accompanying drawing, forming part thereof, and in which the single figure discloses a perspective view of a control instru-

ment casing embodying my new design, looking from a point above and to the left.

The dominant features of the design are shown in full lines in the drawing.

I claim:

The ornamental design for a control instrument casing, substantially as shown and described.

HENRY DREYFUSS.
